Primary Examiner — Mark A Goodwin(74) *Attorney, Agent, or Firm* — Rathe Lindenbaum LLP(57) **CLAIM**

We claim the ornamental design for a mower hitch, as shown and described.

DESCRIPTION

FIG. 1 is a top perspective view of a mower hitch;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a top perspective view of the mower hitch

supporting a ball and mounting fasteners.

The ornamental design which is claimed is shown in solid lines in the drawings. The broken lines in the drawings illustrate environment and form no part of the claimed design.

1 Claim, 7 Drawing Sheets(56)
